(57) **CLAIM**

The ornamental design for a seasoning pod holder, as shown and described.

DESCRIPTION

FIG. 1 is a perspective view of a seasoning pod holder, showing our new design in a closed position;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof;

FIG. 7 is a rear elevation view thereof;

FIG. 8 is a top plan view of the seasoning pod holder in an open position;

FIG. 9 is a perspective view thereof;

FIG. 10 is a top plan thereof, wherein exemplary seasoning pods are placed inside the seasoning pod holder;

FIG. 11 is a perspective view thereof; and,

FIG. 12 is a perspective view thereof, wherein an exemplary seasoning pod is shown removed from the seasoning pod holder.

The broken lines are shown for the purpose of illustrating both parts of the article as well as environmental subject matter of exemplary seasoning pods. None of the broken lines form part of the claimed design.

1 Claim, 11 Drawing Sheets
